UNITED STATES PATENT OFFICE

2,094,763

MACHINE FOR TAPERING STAVE STOCK

Charles M. E. Wendnagel and Frederick W.
Wendnagel, Chicago, Ill.

Application April 22, 1936, Serial No. 75,760

25 Claims. (Cl. 143—168)

This invention relates to improvements in machines for tapering stave stock and it consists of the matters hereinafter described and more particularly pointed out in the appended claims.

5 By the term "stave stock" is meant planks, boards or other lumber, from which the staves for wooden tanks, tubs and the like having a batter or taper toward the top end, are produced. Such a batter or taper is necessary in such tanks 10 so that the usual hoops may be applied thereto and then driven downward toward the bottom to draw the staves closer together to produce a tank having a top diameter and circumference less than the bottom diameter and circumference. 15 The standard batter of a tank, is now recognized as being three-quarters of an inch reduction in diameter for each foot in stave height. This arbitrary figure or relation has been determined by wooden tank manufacturers after long 20 years of experience and is accepted as standard in wood tank making.

In order to produce the proper taper for tanks of different sizes, certain factors or dimensions for each tank must first be known, before it is 25 possible to ascertain the correct taper of the staves going into the particular tank to be made. The factors or dimensions which must first be known are: the outside bottom diameter of the tank; the height of the tank; the overall length 30 of the staves thereof, and the batter or the taper of the tank previously mentioned.

From a combination of these factors or dimensions it is possible to determine the top diameter and circumference as well as the bottom circumference of the tank. The ratio of said top and bottom circumferences will, therefore, approximate the ratio of the width of the top end of any stave thereof, to the width of the bottom end of said stave.

40 With the above in mind, one of the objects of the present invention is to provide a machine for use in connection with a power-driven cutting member and a straight line feeding mechanism therefor, whereby stave stock may be presented 45 to said feeding mechanism for feeding past the cutting mechanism at an angle corresponding to the angle of the taper it is desired to give to the stock.

Another object of the invention is to provide 50 a machine for use in connection with a power-driven rip saw and which will present the advancing end of the stave stock at a tapering angle to the straight line feeding mechanism to be gripped and fed thereby through the saw 55 which will cut the stock to the desired taper.

A further object of the invention is to provide a machine which may be adjusted or set to cut stave stock to the desired taper after the bottom circumference of the tank and the length of the stock going into the tank is known, and this regardless of the width of the stave stock operated upon.

Still another object of the invention is to provide a machine of this kind which includes means for determining the taper to be cut and which means will automatically adjust itself to the proper angular relation with respect to the center line of the saw for a definite width of stave stock to be cut and will maintain said angular relation as the stave stock progresses through 15 the saw.

The above mentioned objects of the invention, as well as others, together with the advantages thereof will more fully appear as the specification 20 proceeds.

In the drawings:

Fig. 1 is a view in side elevation of a machine embodying the preferred form of the invention shown in connection with a conventional power-driven rip saw which it serves;

Fig. 2 is a transverse vertical sectional view on an enlarged scale, through a part of the machine as taken on the line 2—2 of Fig. 1;

Fig. 3 is a fragmentary plan view of the two end parts of the machine and a part of the saw 30 feed mechanism associated therewith;

Fig. 4 is a longitudinal detail vertical sectional view through a part of the machine, on an enlarged scale, as taken on the line 4—4 of Fig. 3;

Fig. 5 is a detail plan view of the parts shown 35 at the left hand end of Fig. 4;

Fig. 6 is a view similar to Fig. 5 with the parts in a different position;

Fig. 7 is a detail plan view on an enlarged scale 40 of the parts at the mid portion of Fig. 3 and which will be more fully referred to later;

Fig. 8 is a detail vertical view on the line 8—8 of Fig. 7 and illustrates more particularly an indicating device for indicating the width of the 45 stave stock to be operated upon;

Fig. 9 is a detail vertical sectional view through the indicating device of Fig. 8 as taken on the line 9—9 thereof;

Fig. 10 is a transverse vertical sectional view 50 on an enlarged scale, through one of the guide or fence holding means embodied in the machine as taken on the line 10—10 of Fig. 7;

Fig. 11 is a bottom plan view on an enlarged 55 scale, of the fence holding dog of Fig. 10 and

shows more particularly the offsetting of the dog teeth for a finer adjustment therefor;

Fig. 12 is a longitudinal detail vertical sectional view through a part of the fence holding mechanism of Fig. 10 as taken on the line 12—12 of said Fig. 10;

Fig. 13 is another longitudinal horizontal sectional view through a part of the machine as taken on the line 13—13 of Fig. 4;

Fig. 14 is a detail vertical sectional view on an enlarged scale, through a part of the machine as taken on the line 14—14 of Fig. 3 and shows more particularly a second indicating device which will be more fully referred to later, and

Fig. 15 is a detail vertical sectional view through the indicating device shown in Fig. 14 as taken on the line 15—15 thereof.

As before stated, the improved machine is especially adapted for use in connection with a straight line power-driven saw and as best shown in Fig. 1, the same is a conventional power-driven rip saw indicated as a whole at 20. Such a saw includes a horizontally disposed saw table 21 suitably supported upon a frame 22. Mounted in said frame is a longitudinally extending, endless feed belt 23 with its top lap substantially flush with the top surface of the table. Above the table is a casing-like saw head 24. In said head is journalled a rotary circular saw or disc 25 which may be adjusted vertically toward and away from the feed belt 23. The head also carries a feed roll 26 at the front of the circular saw to coact with the belt in feeding the pieces of lumber operated upon in a straight line to said saw. The saw feed belt and feed roll are power driven in any suitable manner.

Means are provided which coact with the saw, as a whole, in tapering lumber in the form of stave stock. Said means includes a relatively long stave stock supporting table or platform 27 which extends rearwardly from the rear end of the saw table 21 and is suitably connected thereto so as to form a flush continuation thereof. The table 27 is supported at its intermediate and rear end portions by longitudinally spaced upright legs 28, 29 and 30 respectively.

Preferably the table is made of a metallic plate of suitable dimensions and at the front side thereof are journalled transversely extending loose running rollers or cylinders 31. By the "front side" of said table is meant that side at which the operator is stationed. The rollers 31 are journalled in suitable brackets 32 secured to the underside of the table. The top peripheral portion of each roller extends through an associated opening in the table into a plane slightly above the table top as best appears in Fig. 2. These top peripheral portions of said rollers are adapted to be engaged by the stave stock operated upon as said stock is moved toward the saw so that said rollers provide antifriction supports for said stock.

Mounted on the table, between the rear side thereof and the rollers 31, is a longitudinal guide member 33 hereinafter termed a "fence". The stave stock being operated upon is moved in guided relation up against and along said fence while engaged or supported on the rollers 31. This fence is in the form of an angle bar and is so mounted on the table as to be movable laterally thereof as a straight line, at a right angle to its length. The angle bar forming said fence is so disposed that its vertical flange is toward the front thereof and its horizontal flange is at the bottom thereof and extends toward the rear

side of the table. At longitudinally spaced points on the fence, there are secured to the horizontal flange thereof, transverse extending shoes 34 which engage in transversely extending undercut grooves 35 in the top surface of the table 27. Said shoes are so arranged as to space the fence a short distance above the top surface of the table. This reduces the frictional resistance to transverse movement so that such movement is relatively easy.

In the operation of the machine, as when setting the same for operation upon stave stock of different lengths, this fence at one time or the other is moved toward and away from the plane of the saw. For convenience, this plane is indicated by a longitudinal line 36 in Fig. 3. As before stated the fence 33 is of considerable length and so that both ends thereof move together at the same speed through the same distance, the following structure is provided.

At the rear side of and arranged toward each end of the table 27, are longitudinally spaced members 37 and 38 respectively, each journalled upon an upright stud, 39 and 40 respectively, fixed on the table. The member 37 carries upright crank pins 41 and 42 respectively, and the member 38 carries upright crank pins 43 and 44 respectively. The crank pins on each member are arcuately spaced apart about 90°. The members 37 and 38 although shown herein as discs and will so be hereinafter referred to, function as bell crank levers when the crank pins thereof are considered.

The crank pins 41—43 of said discs are connected to the fence by links 45—46 respectively, which normally extend in planes substantially transversely of the table. The crank pins 42—44 of said discs are connected together by a link or rod 47 which normally extends longitudinally of the table.

It is apparent that when one disc is turned about its axis, the other disc, through the link or rod 47 will turn in the same direction with the same angular velocity because of the equal radii employed between the axis points 39—40 and the pins 42—44. In other words the link or rod 47 synchronizes the movement of the discs. When the discs are so turned, it is apparent that the links 45—46 will cause the fence to move toward and away from the line 36 with a straight line movement.

Turning movement is imparted to the discs manually and the means therefor is as follows:

Secured to the link or rod 47 is a collar 48, which appears in Figs. 2 and 3. This collar carries a depending stem 49 which engages in a longitudinal slot 50 in the front end of an arm 51 that normally extends transversely of the table. Said arm 51 is secured at its rear end to a stud 52 that is journalled in a suitable boss provided therefor at the rear side of the table. Secured to said stud, beneath the table is an actuating lever indicated as a whole at 53. It is to be noted from Fig. 1 that there are two of such levers arranged at longitudinally spaced points along the table so as to be convenient for reaching by the operator from either of two stations which he may occupy at the front of said table. Said two levers are connected by a link 53a whereby actuation of one lever produces actuation of the other.

Each lever 53 is supported at its front end by a supporting bar 54 secured to the underside of the table, the front end of the lever sliding on

said bar. Pivoted to the front end of each lever as by a pin 55, is a lever extension or handle 56. This extension or handle normally hangs pendently from its pin 55 in substantially the plane of the front of the table. The pinned end of said handle carries a stop 57 which when the handle is swung upwardly, engages the front end of the lever and prevents it from being swung through and past its horizontal position. In this position, 10 the handle forms an extension for the lever.

When either lever 53 is swung horizontally in one direction or the other, it will through the associated arm 51 and collar 48 cause a longitudinal movement of the rod or link 41. This of course, will turn the discs 37-38 and through the links 45-46 will cause the fence to be moved toward or away from the line 36 on the table and which as before mentioned, indicates the plane of the circular saw or disc 25.

20 In the operation of the machine, after the fence has been adjusted or set to the desired position as will later appear, the stave stock to be operated upon is placed upon the table, edgewise against the fence. This stock is relatively heavy and in placing it upon the table and against the fence, it engages the fence with considerable force. Therefore, some means is necessary to lock the fence in its adjusted position and in the present instance, such means is as follows:

30 In the top surface of the table, and spaced longitudinally in the same direction from the associated disc 37-38, are rectangular openings 58, see Fig. 10, each of which has its greatest dimension arranged transversely of the table. In this opening is secured a plate 59 having inverted V shaped ribs 60 on its top surface, the ribs extending transversely of the plate and longitudinally of the table. The apex ends of said ribs are flush with the top surface of the table.

40 Secured to the fence 33 in the planes of said ribbed plates 58, are upstanding brackets 61. Each bracket supports on its rear side, a vertically disposed solenoid 62 which includes a downwardly extending core 63. Pivotedly connected to the rear side of each bracket as at 64 is a set of dogs or pawls 65 having V shaped teeth 66 to engage the ribs 60 of the associated plate 59. The teeth of the different pawls or dogs in each set are relatively offset so that a positive engagement of the teeth of one dog or pawl in each set will always occur, no matter what the relative positions of the fence may be with respect to the plates 58.

55 The pawls or dogs in each set are each provided with a slot 67 and a pin 68 extends through the slots in all of the pawls or dogs in the set. The ends of said pin are secured in the side arms 69 of a yoke 70, all as best shown in Fig. 12. Thus the respective dogs in each set are capable of a limited relative floating movement. The mid portion of the cross member 71 of said yoke has a universal joint-like link connection 72 with the core of the associated solenoid. When the solenoid is energized, it will attract its core and through the yoke 70 will lift all dogs or pawls of the set out of engagement with the ribs of the associated plate. When the solenoid is deenergized, the set of dogs drop by gravity toward and engage the ribs of the plate and the fence 33 is locked to the table against movement toward the rear side thereof. When the solenoid is energized, the fence is unlocked from the table so as to be movable with respect thereto.

75 It is of course desired that just previous to the

setting or adjusting of the fence, the same be unlocked with respect to the table so that it can be moved and when thus set or adjusted, it be immediately locked to the table. A convenient way to accomplish this locking and unlocking of the fence in timed relation to the adjusting of the fence is to hook up the solenoids with both the lever extensions or handle 56. Thus when either handle is actuated, the locking and unlocking of the fence occurs in timed relation therewith.

In accordance with the above, there depends from each lever 53 at a point between its ends, a switch casing 73 including fixed and movable contacts. The movable contact includes a pivoted arm 74 at one side of the casing and which arm carries a laterally extending pin 75. Said pin engages in a longitudinal slot 77 in the rear end of a link 78, the front end of which has a pivotal connection 78a with the associated lever 20 extension or handle 56. A conductor cable 80 leads from each switch casing to both solenoids.

When the handle 56 is in the depending position shown in full lines in Fig. 2, the switch 73 is "off" so that the solenoids 62 are deenergized and 25 the pawls 65 are in a position locking the fence to the table. When the handle 56 is swung into the dotted line position shown in said Fig. 2, preparatory to shifting the fence, the link 78 actuates the switch 73 to its "on" position. When 30 the switch is in this position, the solenoids are energized and this withdraws the dogs 65 from engagement with the ribbed plates 59 so as to unlock the fence.

35 On the front end of the fence 33 (the left hand end of the same as appears in Fig. 3) is mounted a casing 79 which for convenience will hereinafter be referred to as a "trigger" casing. As shown in Fig. 3, this casing includes a suitable cover 79a which is omitted in the Figs. 4, 5, and 6 better 40 to disclose the mechanism therein.

In said casing, near the front side thereof is located a longitudinal shaft 80a that is journalled at its ends in upstanding bosses 81-82 respectively, rising from the bottom of the casing. On 45 the extremities of this shaft are pinions 83-84 respectively. In the boss 82 is journalled a tubular shaft 85 carrying a spur pinion 86 and a bevel pinion 87. The bevel pinion 87 meshes with a similar but perpendicularly arranged pinion 88 50 also journalled in the boss and which includes a shaft end 89 to removably receive a crank handle 90. When the pinion 88 is turned in one direction or the other, the shaft 80a through the pinions 84-86 is likewise turned or rotated.

55 The pinion 83 meshes with a pinion 91 on the end of a screw threaded shaft 92 which is so journalled in the boss 81 as to rotate but be held against endwise movement therein. On this shaft is a block 93 having guided engagement at 60 its sides in a longitudinal slot 94 in the casing. When the shaft 92 is turned in one direction or the other, the block is caused to move endwise on the shaft because it is held against turning by its engagement in the slot 94.

65 95 indicates a plate disposed a slight distance above the block and arranged at a suitable angle to the longitudinal plane of the shafts 80a and 92 as best appears in Fig. 5. Pivoted on said plate as at 96 is a trigger 97. The free end of this 70 trigger is made as an arcuate shoe 98 concentric with the pivot point 96 and on the front end of said shoe is a finger or lug 99. The face of the shoe is suitably roughened as by forming it with vertically disposed ridges as best appears in 75

Fig. 5. A spring 100 is arranged between the trigger and a part fixed with respect to the plate 95 to swing the trigger rearwardly. The shoe normally extends to the front of the plane of the front face of the fence so as to be engaged by the advancing end of the stave stock moved along in engagement with the front of the fence toward the saw. This engagement offsets the advancing end of the stave stock laterally toward the front 10 side of the table, just previous to its engagement between the feed belt 23 and feed roll 26. In the front side of the casing 79 is formed an arcuate slot 101 to receive a pin 102 on the shoe when the trigger swings to the limit of its clockwise movement under the action of the stave stock engaged thereagainst when the stock is fed to the saw. This slot is of such arcuate length as to permit the trigger to move clockwise to such a position as to be located entirely within the casing. At 20 that time a plate 103 shown in dotted lines in Fig. 5, may be inserted into the casing to block off the trigger to render it inoperative. This feature is advantageous when it is desired to rip saw lumber in a straight line, using the fence only as a straight line sawing guide.

In the plate 95 between its front and rear edges is a longitudinal slot 104 and on the rear edge of said plate at the ends thereof are bosses 105—106 respectively. Journalled in said bosses for rotative movement only, is a threaded, longitudinal shaft 107 and engaged on said shaft is a traveler block 108. This block includes an extension 109 which extends transversely of and overhangs the plate 95 so as to cross the slot 104 therein. This extension carries a pin 110 which engages the slot 104 and is operatively connected to the traveller block 93 on the shaft 92 before mentioned.

To that end of the threaded shaft 107 journalled in the boss 106 is secured one end of a flexible shaft 111. The other end of said flexible shaft is secured to one end of a stub shaft 112 that has a splined engagement in the tubular shaft 85 before mentioned. Threaded into the other end of the stub shaft is one end of a bolt 113 the other 45 end of which has a head 114. An expansion spring 115 surrounds that part of the bolt between said head and a bearing bracket 116 in the casing 79. This spring arrangement keeps the flexible shaft extended and relatively straight and 50 eliminates such kinks as may tend to form therein. It is apparent that due to the splined connection between the tubular shaft 85 and the stub shaft 112, when the pinion is turned in one direction or the other, the stub shaft and its associated flexible shaft are likewise turned.

The plate boss 106 has one end of an arm 117 secured thereto. The other end of said arm is pivotally connected as at 118 to one end of a curved link 119 (see Fig. 3) the other end of 60 which is pivotally connected with respect to the table as at 120.

Mounted on the arm 117 between the casing 79 and link 119 is an upright bracket 121 for supporting an indicator 122, calibrated to coordinate the base diameters of tanks with stave stock height and batter thereof as shown by index numbers thereon, for which the machine is capable of tapering stave stock. This indicator includes a segmental casing 123 with an arcuate 65 face plate 124 upon which appears spaced calibrations to represent certain index numbers to coordinate the base diameter with stave stock height or length and batter. Journalled in said casing concentric with the face plate 124 is a drum 125, a spring 126 being interposed between

the drum and casing to normally turn the drum in one direction. A hand or pointer 127 is carried by the drum to coact with the calibrations on the face plate. One end of a flexible band 128 is wrapped partway around the drum and is then secured thereto and the other end of this band is operatively attached to the traveler block 108. When said traveler block moves longitudinally of its threaded shaft 107 by reason of the turning of the crank handle 89, the hand or pointer 127 is caused to move to a position on the face plate corresponding with the position of the block 108 on its shaft.

130 (see Figs. 7, 8, and 9) denotes a device for indicating the width of the stave stock being 15 operated upon. This device is positioned toward the rear side of the table near the disc 37. It includes an upright casing 131 arranged transversely of the table and arranged to straddle the link 47. At the top of the casing is a semi-circular face plate 132, suitably calibrated to indicate the widths of different stave stock in 20 inches.

A stud 133 is fixed in said casing concentric with the face plate and journaled thereon is a 25 pinion 134. A hand or pointer 135 is carried by said pinion to coact with said face plate. The casing is provided with a horizontal guideway 136 beneath the pinion and upon which slides a rack bar 137 that meshes with the bottom side of the 30 pinion. When the rack bar is moved longitudinally in either direction, it is apparent that the hand will swing with respect to the face plate.

The rack bar 137 is arranged transversely of the table and its rear end has a pin and slot engagement in the bent end of an arm 138. This arm forms part of a lever 139 which has a vertical pivotal connection 140 with the table 27. The other arm 141 of said lever passes above the disc 37 and then has a bend therein to extend 40 under the trigger casing 79. The bent end of said arm has a longitudinal slot 142 therein, in which a pin 143 depending from the trigger casing engages.

It is to be borne in mind that the usual run 45 of stave stock is of random width. The fence 33 should be set a distance away from the line 36 of the saw, equalling the width of the stock used.

The operator, therefore, grasps one of the handles 56 and swings it upwardly into the position 50 forming an extension of the lever 53. This unlocks the fence with respect to the table. The lever 53 is then swung in that direction which will cause the desired movement of the fence, that is, toward or away from the line 36 indicating the plane of the saw. In this movement of the fence, it will through the pin and slot connection 142—143 with the lever 139, cause said lever to swing about its pivot 140. This movement of the lever, through its arm 138 and the 60 rack bar 137, will cause the pointer 135 to swing about the face plate 132. When the pointer 135 reaches that numeral on the face plate which corresponds in inches with the width of the stock operated upon, the operator merely releases the 65 handle or extension. The handle then swings downwardly by gravity and operates through the link to move the switch 73 to its "off" position. This deenergizes the solenoids 62 and the pawls 65 gravitate into an engagement with the ribbed 70 plate 59. The fence is then locked to the table 75 in the desired position.

The operator then pushes the stave stock now on the table, toward the fence so that one edge thereof engages up against the fence. This 75

should dispose the other edge of the stave stock up to approximately the plane of the line of the saw. The operator then moves the stave stock forwardly along and in parallelism with the fence toward the saw. As the front end of the stave stock approaches trigger 97, its end engages the finger 99 as shown in full lines in Fig. 5, and causes the trigger to swing clockwise. The shoe or face of said trigger then moves or offsets the advancing or front end of the stave stock away from the fence as shown in dotted lines in Fig. 5. This disposes the stock at that angle to the fence which corresponds to the angle of the taper to be cut for the stave. This lateral offset movement of the advancing end of the stave stock occurs just before the stock is gripped between the feed roll 26 and feed belt 23. The feed roll and belt feeds the stock in a straight line to the saw and as the stock is presented to the saw at an angle to the fence corresponding to the desired taper, the saw cuts a strip from the front lateral margin of the stock which is wider at the front end and tapers toward the rear end.

As the stock passes through the saw, the trigger swings into the casing 79 out of the way and as the rear end of the stock passes the same, the trigger snaps back to its original position.

As the "trigger" casing 79 is fixed with respect to the fence 33, it is apparent that the upstanding bosses 81-82 in said casing are likewise fixed or immovable with respect to said fence. It is, therefore, evident that the block 93 and the pin 110 carried thereby may be definitely adjusted with respect to the fence by means of the screw 92.

It is to be noted that the pivot 120 for the arm 119 is rigid with the table 27 so that the points 110 and 120 are relatively fixed in any one of the adjustments the fence may have upon the table 27. Therefore, the links 119 and 117 (the latter of which includes the plate 95) which are connected through the pivot 118, may be considered as a solid link connecting the two points 110-120 together.

It is evident that having the three-unit linkage, the same constitutes a constrained mechanism. In this mechanism, however, so far as the linkage is concerned, the slot 104 in the plate 95 may be considered simply as a hole for the affixing of the pin 110. This is true because the block 108 is threaded upon the screw 107 and because of the parts 105-106 and the restraining collars associated therewith. Therefore, the block 108 may be considered as fixed in any given setting of the plate 95. Therefore, reasonable working forces in any horizontal direction on the plate 95 cannot cause the same to pivot about the pin 110 because said plate is a part of one link in a three-unit constrained mechanism.

When stave stock engages the trigger 97 if it cannot be pushed longitudinally of itself nor can any compound translational and pivotal movement of the trigger be produced by the stave stock in its feed to the saw to disturb or disrupt the set position of the plate 95.

Assume that wider stave stock is to be operated upon. This requires a resetting of the fence to accommodate such wider stock. The operator knowing the width of the stock operated upon, grasps one of the handles 56 and swings it upwardly into a position wherein it forms an extension of the lever 53 and then swings it laterally until the indicator 135 lines up with that calibration numeral on the face plate 132 which corresponds to the width of the stock operated upon. In this movement of said lever, the fence is moved

rearwardly so that it is spaced from the line of the saw a distance corresponding to the width of the stock. This change in width appears in Fig. 6. When the handle 56 is released, the fence is locked in its newly set or adjusted position. In this movement of the fence into its new position, no manual resetting of the trigger 97 is necessary because it occurs automatically in the following manner:

In the movement of the fence toward the rear side of the table into its new position, the pin 110 for the plate moves rearwardly therewith. As the distance between the points 118 and 96 is less than that between the points 118 and 110, the point 96 will not move with so great a velocity as the point 110. Consequently, in the rearward movement of the fence, the dog is caused to protrude a greater distance beyond the plane of the front of the fence into the angular position shown in Fig. 6.

Therefore, when the piece of wider stock is moved forward along the fence, its advancing or front end engages the trigger as before to be offset laterally toward the front of the table 27, across the line of the saw into an angular position with respect to the fence that corresponds to the taper to be cut. When the stock is grasped by the feed roll 26 and feed belt 23, it is passed through the saw so that a tapered strip is removed from one side thereof.

Assume now that it is desired to taper stave stock for a tank having a different index number value. This, of course, requires a resetting of the trigger so as to cause said trigger to produce a taper, different from that previously produced, to meet the requirements of taper for the staves of the tank of said different index number value.

With the base diameter shown, the operator turns the crank handle 90 and this produces rotation of the threaded shafts 92 and 107 and a movement of the traveler blocks 93 and 108, thereon. In this movement of said blocks, the pin 110 moves along the slot 104 and this varies the distance between the pin and the axis 96 of the trigger 97. By reason of the connection between the plate arm 117 and link 119, the plate 95 is moved into a different angular position so that the trigger pivot 96 swings in an arc to be moved toward or away from the plane of the front face of the fence. This projects the shoe of the trigger outwardly beyond the plane of the front face of the fence or retracts it inwardly from said plane so that the trigger is moved into that position which will offset the advancing or front end of the stave stock toward the front of the table to give it the angle corresponding with the desired taper. In the movement of the traveler blocks, the band 128 will cause movement of the indicator 127. When the indicator reaches that numeral on the face plate 124, corresponding to the index number for the particular tank for which the staves are to be made, the crank handle is released. The trigger is now in a position to provide that taper required in said particular tank.

It is to be noted that the trigger mechanism described serves the purpose of offsetting the advancing end of the stave stock, away from the plane of the front face of the fence so as to provide the desired taper. The amount of this offset varies with the width of the stave stock operated upon and in this respect it automatically adjusts itself in accordance with the amount of variation. This happens because when the fence is moved in adjustment toward the rear side of the table, the trigger is automatically

caused to protrude a greater distance from the front face of the fence into a new position. This, of course, changes the offset action of the trigger when the wider stave stock approaches the same to give the necessary taper therefor.

The amount of offset action must also be varied with respect to tank proportions, that is, the ratio of base diameter to the height of the tank. By moving the plate 83, through the manipulation of the crank handle 88, it will be seen that the relative movement between the fence and trigger will be changed.

In any given proportion, however, the movement of the trigger with respect to the plane of the saw as indicated by the line 36, is proportional to and not the same as the movement of the fence. For wider pieces of stave stock, the offset produced by the trigger is greater than that for the narrower stave stock.

It will be seen that when tank dimensions are known, the machine may be set to taper the stave stock in accordance with said dimensions.

When no taper is desired, as when trimming stave stock for a cylindrical tank requiring no taper, the trigger mechanism may be locked out of operation by the use of the plate 103 before mentioned. Under such conditions, the fence may be adjusted for different widths of stock and this stock may be fed to the saw in a plane parallel with the fence and the line of cut of the saw.

While in describing the invention, we have referred in detail to the form, arrangement and construction of the various parts thereof, the same is to be considered only in the illustrative sense so that we do not wish to be limited thereto except as may be specifically pointed out in the appended claims.

We claim as our invention:

1. In combination with a power-driven cutting member and means for feeding stave stock thereto in a straight line, a stock supporting table, means mounted on said table for a lateral adjustable movement toward and away from the plane of said line for engagement by the stock to be tapered for guiding the same to said feeding means at an angle corresponding to the angle of the taper to be given the stock, manually operable means connected to the first mentioned means for imparting said lateral adjustable movement thereto, and means controlled by said manually operable means for locking and unlocking said laterally adjustable means with respect to the table said locking and unlocking means including a set of toothed dogs movable with said laterally adjustable means and coacting parts on said table with which said dogs are adapted to engage and disengage.

2. In combination with a power-driven cutting member and means for feeding stave stock thereto in a straight line, a stock supporting table, means mounted on said table for a lateral adjustable movement toward and away from the plane of said line for engagement by the stock to be tapered for guiding the same to said feeding means at an angle corresponding to the angle of the taper to be given the stock, means carried by said first mentioned means and normally engaging parts of the table for locking the first mentioned means thereto, manually operable means connected to said first mentioned means for imparting said lateral adjustable movement thereto, and electrical means mounted on the means on the table and controlled by said man-

ually operable means for releasing said locking means.

3. In combination with a power-driven cutting member and means for feeding stave stock thereto in a straight line, a stock supporting table, a fence mounted thereon for lateral movement toward and away from the plane of said line and adapted for engagement by the stock to be tapered in guiding the same toward said feeding means, means supported by the fence when the fence is in one position on the table for stave stock of one width and adapted for engagement by the advancing end of the stave stock as it approaches said feeding means for moving said end laterally away from the fence into one angular position corresponding to the angle to be given said stave stock of one width, and means operating on said means supported by the fence as the same moves into another position on the table to accommodate stock of another width, for imparting a different amount of lateral movement to the advancing end of said stock to move the same into a different angular position corresponding to the angle of the taper to be given said stock of different width.

4. In connection with a power-driven cutting member and means for feeding stave stock thereto in a straight line, a stock supporting table, a fence mounted thereon for lateral movement toward and away from the plane of said line and adapted for engagement by the stock to be tapered for guiding the same toward said feeding means, a member supported by said fence but capable of a lateral independent movement with respect to the plane of the front face of the fence and adapted for engagement by the advancing end of the stock as it approaches said feeding means for moving said end laterally away from the fence into an angular position corresponding to the angle of the taper to be given the stock, and means for projecting and retracting said member with respect to the fence, independent of the lateral movement of the fence for moving the advancing end of the stave stock into a different angular position with respect to the fence and which corresponds to a different angle of taper to be given the stock.

5. In combination with a power-driven cutting member and means for feeding stave stock thereto in a straight line, a stock supporting table, a fence mounted thereon for lateral movement toward and away from the plane of said line and adapted for engagement by the stock to be tapered for guiding the same toward said feeding means, a member pivotally mounted on the fence and adapted for engagement by the advancing end of the stave stock as it approaches said feeding means for moving said end laterally away from the fence into an angular position corresponding to the angle of taper to be given the stock, and means for moving the pivotal axis of said member toward or away from the plane of the face of said fence, independent of the lateral movement of the fence so that said member in its engagement by the advancing end of the stave stock moves said stock into a different angle of taper to be given the stock.

6. In a machine of the kind described, stock cutting means, a fence, a pivotally mounted member arranged with a portion thereof projecting outwardly beyond the plane of the face of said fence, and adapted for engagement by the advancing end of the piece of stock moved along the fence toward the stock cutting means for deflecting said advancing end into the desired angle.

as said end approaches the stock cutting means, and means for changing the position of the axis of said member with respect to the plane of said face of the fence.

5 7. In a machine of the kind described, a fence, a plate member, means providing a movable pivot for said plate member with respect to the fence, and a trigger pivoted on said plate so as to have a portion project beyond the plane of the 10 face of said fence.

10 8. In a machine of the kind described, a fence, a plate member movable toward and away from said fence, a pivot for said plate member, a pair of rotatable threaded shafts, means for rotating 15 said shafts simultaneously, traveler blocks on said shafts and operatively engaged with the pivot for the plate member so as to change the position of said pivot with respect to the fence, and a trigger pivoted on said plate member and having 20 a portion projecting beyond the plane of the face of said fence.

15 9. A machine for cutting stave stock for tanks having a batter, said machine comprising a stock support, stock cutting means, means on said support adapted to be set to position different widths of stock with respect to the plane of said cutting means, said last mentioned means including mechanism for arranging the stock at a certain angle, said mechanism being operated by said 25 stock positioning means in the setting thereof for a piece of stock of certain width to arrange said piece of stock at that taper angle to said plane as required by its width for said batter.

30 10. A machine for cutting stave stock for tanks having a batter, said machine comprising a stock support, stock cutting means, means on said support adapted to be set to position different widths of stock with respect to the plane of said cutting means, a member pivotally mounted with respect 35 to said positioning means, and means connecting said positioning means and said pivotally mounted member whereby the setting of said positioning means will vary the setting of said member to operate in each setting of said positioning means 40 to move the piece of stock operated upon into that taper angle required by its width for said batter.

45 11. A machine for cutting stave stock for tanks having a batter, said machine comprising a stock support, stock cutting means, means on said support adapted to be set to position different widths of stock with respect to the plane of said cutting means, a pivoted member movable with said positioning means, and mechanism connecting to 50 said member and said positioning means and operating when said positioning means is set for a certain width of stock to cause said pivoted member to move said piece of stock operated upon into that taper angle required by its width 55 for said batter.

55 12. A machine for cutting stave stock for tanks having a batter, said machine comprising a stock support, stock cutting means, means on said support adapted to be set to position different widths of stock with respect to the plane of said cutting means, stock end engageable means and means operatively connecting the same to said last mentioned means, said stock end engageable 60 means in each setting of said positioning means operating through said connecting means to move the piece of stock operated upon into that taper angle to said plane as required by its width for said batter, and means for moving said stock 65 and said cutting means relative to each other 70

75 while maintaining said taper angle for said piece of stock.

13. A machine for cutting stave stock for tanks having a batter, said machine comprising a stock support, stock cutting means, means on said support and arranged substantially parallel with the plane of the cutting means and movable toward and away from said plane to position different widths of stock with respect to said plane, stock end engageable means and means operatively connecting the same to said last mentioned means, said stock end engageable means when said stock positioning means is moved toward or away from said plane for a certain width of stock, operating through said connecting means to move the piece of stock operated upon into that taper angle to said plane as required by its width for said batter. 10 15

14. A machine for cutting stave stock for tanks having a batter, said machine comprising a stock support, stock cutting means, means on said support and arranged substantially parallel with the plane of the cutting means and movable toward and away from said plane to position different widths of stock with respect to said plane, mechanism associated with said positioning means and including a member projecting into the path of the piece of stock moved along said positioning means toward the stock cutting means, and means connecting said stock positioning means and said mechanism for moving said member into a position that causes said piece of stock as it engages the same to move into that taper angle to said plane as required by the width of said piece of stock for said batter. 20 25 30 35

15. A machine for cutting stave stock for tanks having a batter, said machine comprising a stock support, stock cutting means, means on said support and arranged substantially parallel with the plane of the cutting means and movable toward and away from said plane to position different widths of stock with respect to said plane, a member pivotally mounted with respect to said positioning means, and means connecting said positioning means and said member whereby the setting of said positioning means will vary the setting of said member, to move said piece of stock into that taper angle to said plane as required by its width for said batter. 40 45 50

16. A machine for cutting stave stock for tanks having a batter, said machine comprising a stock support, stock cutting means, a fence arranged on said support parallel with the plane of said cutting means, coacting means on said support and fence respectively, providing a guided movement of said fence toward and away from said plane in substantial parallelism therewith, manually operable means associated with said support for imparting movement to said fence toward and away from said plane, mechanism associated with said fence for arranging the stock at a certain angle with respect to said fence, and means connecting said fence and said mechanism and operating said mechanism as said fence is moved toward or away from said plane to position a certain width of stock with respect to said plane, to move said piece of stock into that taper angle to said plane as required by the width thereof for said batter. 55 60 65 70

17. A machine for cutting stave stock for tanks having a batter, said machine comprising a stock support, stock cutting means, a fence arranged on said support parallel with the plane of said cutting means, coacting means on said support and fence respectively, providing a guided move- 75

ment of said fence toward and away from said plane in substantial parallelism therewith, manually operable means associated with said support for imparting movement to said fence toward and away from said plane, means operable in timed relation with said manually operable means for unlocking and locking the fence with respect to the support, mechanism associated with said fence for arranging the stock at a certain angle with respect to said fence, and means connecting said fence and said mechanism and operating the latter as said fence is moved toward or away from said plane to position a certain width of stock with respect to said plane, to move said piece of stock into that taper angle to said plane as required by the width thereof for said batter.

18. A machine for cutting stave stock for tanks having a batter, said machine comprising a stock support, stock cutting means, a fence arranged on said support parallel with the plane of said cutting means, coacting means on said support and fence respectively, providing a guided movement of said fence toward and away from said plane in substantial parallelism therewith, manually operable means associated with said support for imparting movement to said fence toward and away from said plane, pivoted means movable with said fence for arranging the stock at a certain angle with respect to said fence, and means connecting said fence and said pivoted means and operating the latter as said fence is moved toward or away from said plane to position a certain width of stock with respect to said plane, to move said piece of stock into that taper angle to said plane as required by the width thereof for said batter.

19. A machine for cutting stave stock for tanks of different heights and end diameters and having a batter, said machine comprising a stock support, stock cutting means, means on said support adapted to be set to position different widths of stock with respect to the plane of said cutting means, means associated with said positioning means and adapted to be set to produce that taper angle for the piece of stock operated upon, with respect to said plane as required by the height and end diameter of the tank being made so that said angle will accord with said batter, and means connecting said positioning means and said means associated therewith to actuate the latter when said stock positioning means has been moved into the desired position on said support.

20. A machine for cutting stave stock for tanks of different heights and end diameters and having a batter, said machine comprising a stock support, stock cutting means, means on said support adapted to be set to position different widths of stock with respect to the plane of said cutting means, means associated with said positioning means and including a member carried thereby and adapted to be set to produce that taper angle for the piece of stock operated upon, with respect to said plane as required by the height and end diameter of the tank being made so that said angle will accord with said batter, and means operatively connecting said stock positioning means and said last mentioned means to actuate said member when said stock positioning means has been set for a different width of stock, to move the piece of stock operated upon into that taper angle to said plane required by its width for said batter.

21. A machine for cutting stave stock for tanks of different heights and end diameters and having a batter, said machine comprising a stock

support, stock cutting means, means on said support adapted to be set to position different widths of stock with respect to the plane of said cutting means and means associated with said positioning means and adapted to be set to produce that taper angle for the piece of stock operated upon with respect to said plane as required by the height and diameter of the tank being made so that said angle will accord with said batter, means operatively connecting said stock positioning means and said last mentioned means to actuate the latter when said positioning means has been set for a different width of stock to move the piece of stock operated upon into that taper angle to said plane required by the width of said stock for said batter, and a gauge having matter thereon representing certain index values as to height and end diameters of certain tanks, said gauge including a part connected to said means associated with said positioning means for visibly indicating the index value of the setting of said means associated with said positioning means.

22. A machine for cutting stave stock for tanks of different heights and diameters and having a batter, said machine comprising a stock support, stock cutting means, a fence on said support parallel with the plane of said cutting means and movable toward and away from the same to position different widths of stock with respect to said plane, means associated with the fence and adapted to be set to produce that taper angle for the piece of stock operated upon with respect to said plane as required by the height and end diameter of the tank being made so that said taper angle will accord with said batter, and means for connecting said settable means to said fence and operating as said fence is moved from one position to another for varying the setting of said settable means to coordinate the same with the position of the fence.

23. A machine for cutting stave stock for tanks of different heights and diameters and having a batter, said machine comprising a stock support, stock cutting means, a fence on said support, parallel with the plane of said cutting means and movable toward and away from the same to position different widths of stock with respect to said plane, means associated with the fence and adapted to be set to produce that taper angle for the piece of stock operated upon with respect to said plane as required by the height and end diameter of the tank being made so that said taper angle will accord with said batter, said settable means including a member adapted for engagement by the piece of stock as it moves along the fence and means for connecting said member to said fence and operating as said fence is moved from one position to another for varying the position of said member to move the piece of stock operated upon into that angle to said plane as required by its width for said batter.

24. A machine for cutting stave stock for tanks of different heights and end diameters and having a batter, said machine comprising a stock support, a cutting means, means on said support adapted to be set to position different widths of stock with respect to the plane of said cutting means, settable means associated with said positioning means for offsetting one end of the piece of stock operated upon to move said piece of stock into that taper angle with respect to said plane as required by the height and diameter of the tank being made so that said taper angle will accord with said batter, means connecting said positioning means and said settable means so that said set-

table means is varied with the setting of the positioning means and means for feeding said piece of stock to said cutting means in a straight line while maintaining said taper angle.

- 5 25. A machine for cutting stave stock for tanks of different heights and end diameters and having a batter, said machine comprising a stock support, a cutting means, means on said support adapted to be set to position different widths of 10 stock with respect to the plane of said cutting means, settable means associated with said positioning means for offsetting one end of the piece of stock operated upon to move said piece of stock into that taper angle with respect to said plane as 15 required by the height and diameter of the tank

being made so that said taper angle will accord with said batter, means connecting said positioning means and said settable means so that said settable means is varied with the setting of the positioning means, and means for feeding said piece of stock to said cutting means in a straight line while maintaining said taper angle, said settable means when said stock positioning means has been set for a different width of stock, operating through said connecting means to move the 10 piece of stock operated upon into that angle to said plane as required by its width for said batter. 5
